UNITED STATES PATENT OFFICE

114,192

DESIGN FOR A STATUETTE

Rowland Lyon, Chevy Chase, Md.

Application December 2, 1937, Serial No. 73,323

Term of patent 3½ years

To all whom it may concern:

Be it known that I, Rowland Lyon, a citizen of the United States, residing at Chevy Chase, in the county of Montgomery and State of Maryland, have invented a new, original, and ornamental Design for Statuettes, of which the following is a specification, reference being had to the accompanying drawing, forming part thereof.

Fig. 1 is a plan view and Fig. 2 is an elevation of a statuette, showing my new design.

I claim:

The ornamental design for a statuette, as shown.

ROWLAND LYON.
